US00D862256S

(12) **United States Design Patent** (10) Patent No.: **US D862,256 S**
Hasegawa et al. (45) Date of Patent: ** Oct. 8, 2019

(54) **PYROMETER**

(71) Applicant: **EKO INSTRUMENTS CO., LTD.**,
Tokyo (JP)

(72) Inventors: **Toshikazu Hasegawa**, Tokyo (JP);
Shuji Yoshida, Tokyo (JP)

(**) Term: **15 Years**

(21) Appl. No.: **35/505,206**

(22) Filed: **Dec. 28, 2017**

(80) **Hague Agreement Data**

Int. Filing Date: **Dec. 28, 2017**

Int. Reg. No.: **DM/099443**

Int. Reg. Date: **Dec. 28, 2017**

Int. Reg. Pub. Date: **Jun. 29, 2018**

(30) **Foreign Application Priority Data**

Jul. 5, 2017 (JP) 2017-014544

(51) **LOC (12) Cl.** **10-04**

(52) **U.S. Cl.**

USPC **D10/57**

(58) **Field of Classification Search**

USPC D10/106.5, 47, 46, 52, 103, 57
CPC ... G01J 1/04; G01J 1/02; G01J 1/0271; G01S
3/7861
